The schedule referred to in these Letters Patent, and making part of the same,

To whom it may concern:

Dec. 1117

2

Be it known that I, James Bogle, of West Newton in the County of Middlesex and Commonwealth of Massachusetts, have invented or produced a new and Original Design for an impression by printing on Fabrics known as Floor Oil-Cloths, and I do hereby declare that the accompanying Pattern of this date Marked "No. two" and having my Signature attested by N. T. Dow and F. O. Prince as witnesses, fully represents said design and will enable any one skilled in the art to which it relates, to repeat it for practical use -

The colors and the adjustment of them may in the use of the Design be the same as in said Pattern or be varied at pleasure.

The Design of whatever size, in whatever colors in kind or number, or in whatever contrast or blending of colors or of light and shade is the thing I claim as new and as my Invention and desire to secure by the Letters Patent of the United States to my assignees agreeably to my assignment and Petition of this

9th. day of June, 1809.
